UNITED STATES PATENT OFFICE.

KARL ARNSTEIN, OF FRIEDRICHSHAFEN-ON-THE-BODENSEE, GERMANY, ASSIGNOR
TO LUFTSCHIFFBAU ZEPPELIN GESELLSCHAFT MIT BESCHRANKTER HAFTUNG,
OF FRIEDRICHSHAFEN-ON-THE-BODENSEE, GERMANY.

WIRE AND ROPE CLAMPING DEVICE.

Original application filed October 23, 1922, Serial No. 596,488. Divided and this application filed April 16, 1924. Serial No. 706,856.

To all whom it may concern:

Be it known that I, KARL ARNSTEIN, a citizen of Czechoslovakia, residing at Friedrichshafen-on-the-Bodensee, Germany, have 5 invented certain new and useful Improvements in Wire and Rope Clamping Devices, for which I have filed an application in Germany October 21, 1921, and of which the following is a specification.

10 My invention has reference to clamping means for wires, wire ropes and the like, and it particularly provides for the passing of the wires or ropes substantially or approximately or exactly through the median line 15 of the coupling. In accordance with my invention, the wire or rope to be tightened or the wires or ropes to be intersectingly connected or coupled with each other or with other parts are passed between oppositely 20 concave and convex curved clamping surfaces so as to be deflected.

This application is a division of my application for patent filed October 23, 1922, Serial No. 596,488.

25 The clamping surfaces may be formed of complete discs provided with sector-shaped projections and sockets, the outer surfaces of which are spherically curved in opposite sense, and engaged with each other. The 30 clamping members are connected to each other by several screws, eccentrically arranged, in such a manner that the wires are passed between the two screws at the desired angle, recessed portions being provided for 35 the passage of the wires between the apexes of the projecting sectors.

The clamping device according to my invention offers the advantage that the wires are held fast along an extended clamping 40 surface and are maintained between only two clamping members, each of the wires being passed between the gaps presented by the projection of one of the members and between the projections of the other member. This affords the possibility of constructing a coupling device of very compact form requiring very little space. The 45 clamping means, according to my invention, is adapted both for the clamping in position of single or several wires or the like running in one direction only, as well as for the reception of a plurality of crossing or inter-

secting wires. It is particularly adapted for special purposes, for example, in the building of hulls for air-ships of the rigid 55 type, wherein wires, wire ropes and the like are to be secured to sheet metal members, flange bars and the like.

In the drawings affixed to this specification and forming part thereof, a device embodying my invention is shown by way of example. In the drawings—

Fig. 1 is a side view, the clamping members being shown somewhat separated from each other.

Fig. 2 is a cross section on the line II—II in Fig. 1, and

Fig. 3 is a perspective view, the clamping members being separated.

Referring to the drawings, each of the 70 two clamping discs *a* and *a*¹ is provided with projecting sectors *b* and *b*¹, respectively, the outer surfaces of which are spherically curved and which are adapted to engage in corresponding recesses *c* and *c*¹, respectively, of the other clamping member, the bottoms of the gaps being spherically curved in conformity therewith. The curvature of the segmental surfaces determines the bending 80 of the wire to be gripped, as shown for instance in Fig. 1 of the drawing. The wires to be clamped or coupled are arranged to extend each across the gaps or recesses of one and the sectors of the other clamping member, a gap *y* separating the convex-shaped sectors of each member.

The clamping members are pressed against one another by a pair of screw bolts *e* with nuts *f*, the bolts being fixed in one 90 of the members with about one half of the circumference of the foot portion of each bolt extending through a semi-cylindrical groove *x* provided in a lateral face of a sector of this member, while similar grooves are provided in the lateral faces of the sectors of the other member for the reception 95 of the free ends of the screw bolts.

Fig. 1 shows the way in which the wires can be fixed by means of this device to a plate *g* or to a strut girder or the like.

100 The particular configuration, relative position and cooperation of the several parts of the novel device allows clamping or coupling a pair of intercrossing wires, ropes or

the like right in the diameters of the coupling discs with the wires or the like intersecting the centre of the clamping device.

I wish it to be understood that I do not desire to be limited to the exact details of construction shown and described, for obvious modifications will occur to a person skilled in the art.

I claim.

10 1. Clamping and coupling device for wires, ropes and the like, comprising in combination, two substantially disc-shaped coupling members, convex surfaces on each disc with two oppositely disposed concave recesses, the convex portions of each disc fitting in the concave recesses of the other disc, a central gap between the convex por-

tions of each disc and means for clamping said discs together.

2. Clamping and coupling device for wires, ropes and the like comprising in combination two substantially disc-shaped coupling members, convex surfaces on each disc with two oppositely disposed concave recesses, the convex portions of each disc fitting in the concave recesses of the other disc, a central gap between the convex portions of each disc and screw bolts extending through said discs with part of their circumferences surrounded by grooves in diametrically opposite lateral faces of said convex portions.

In testimony whereof I affix my signature.

KARL ARNSTEIN.
